UNITED STATES PATENT OFFICE.

PETER AUGUST NORDQUIST, OF OGDEN, UTAH, ASSIGNOR TO DETACHABLE PLOW
SHARE EDGE MANUFACTURING COMPANY, OF OGDEN, UTAH, A CORPORATION.

DETACHABLE-PLOW-EDGE-BENDING MACHINE.

1,374,094.

Specification of Letters Patent.

Patented Apr. 5, 1921.

Application filed April 14, 1920. Serial No. 373,776.

To all whom it may concern:

Be it known that I, PETER A. NORDQUIST, a citizen of the United States, residing at Ogden, in the county of Weber, State of Utah, have invented a new and useful Detachable-Plow-Edge-Bending Machine; and I do hereby declare the following to be a full, clear, and exact description of the invention, such as will enable others skilled 10 in the art to which it appertains to make and use the same.

The invention relates to bending machines and has for its object to provide a bending machine particularly adapted for longitudinally bending strips of metal, which strips are adapted to be used as detachable plow edges.

A further object is to provide a machine for bending strips of metal longitudinally comprising an endless male die carrying chain which is intermittently moved, thereby moving one of the chain carried male dies to a position where it will register with a female die carried by a pivoted jaw. Also 25 to provide gripper means for gripping the metal strip and holding the same so that it will be forced into the female die carried by the pivoted jaw so that the same will be longitudinally bent.

30 A further object is to provide means whereby the male die carrying chain, the pivoted jaw, the intermittent movement of male die carrying chain and the opening of the gripper jaws and the pivoted jaws will be operated from a main drive shaft.

40 A further object is to provide an adjustable eccentric bar, which bar actuates a dog which co-operates with a ratchet wheel for intermittently moving the die carrying chain.

45 A further object is to provide cam means for actuating gripping jaws of the pivoted jaw member, whereby said gripping jaws will be closed when the pivoted jaw moves inwardly for a bending operation. Also to provide means whereby the bent metallic strips will be removed from the male bending dies as the chains move incident to the intermittent movement thereof.

50 With the above and other objects in view the invention resides in the combination and arrangement of parts as hereinafter set forth, shown in the drawings, described and claimed it being understood that changes 55 in the precise embodiment of the invention

may be made within the scope of what is claimed without departing from the spirit of the invention.

In the drawings:—

Figure 1 is a side elevation of the bending machine.

Fig. 2 is a front elevation of the bending machine.

Fig. 3 is a longitudinal vertical sectional view taken on line 3—3 of Fig. 2.

Referring to the drawings, the numeral 1 designates a frame and 2 the sides thereof. The rear end of the frame is preferably lower than the front end and has rotatably mounted in bearings 3 thereof a shaft 4, on one end of which shaft a drive wheel 5 is secured. Power may be belted to the drive wheel 5 or if so desired power may be attached direct to the shaft 4. The shaft 4 is also provided with a gear 6 which meshes with a large gear 7 carried by shaft 8, which shaft is rotatably mounted in bearings of the side 2 of the frame. Secured to one end of the shaft 8 is a gear 9, which gear meshes with the large gear 10 which is rotatably mounted on stub shaft 11 of the frame. It will be seen that as the pulley 5 moves in the direction of the arrow *a* that the gear 7 will rotate in the direction of the arrow *b*, which will, through the medium of the small gear 9 cause the large gear 10 to rotate in the direction of the arrow *c*. By providing the train of gears it will be seen that the power will be materially increased and at the same time the speed of rotation of the large gear 10 will be decreased so as not to operate the mechanism at too high a speed.

Rotatably mounted in bearings 12 and 13 adjacent the forward end of the frame 1 are shafts 14 and 15. Secured to the shafts 14 and 15 are spaced sprockets 16 and around which sprockets endless chains 17 pass. The sprocket chains are transversely connected by die holders 18, in which die holders male dies 19 are carried. The male dies 19 are triangular in shape and are adapted to bend strips of metal longitudinally so that they will be substantially V-shaped in cross section. Secured to one end of the shaft 16 is a ratchet wheel, which ratchet wheel is adapted to be intermittently rotated so as to intermittently move the male dies 19. The intermittent movement of the ratchet wheel 20 is accomplished by means of the rockable member 21, which is rockably 110

mounted on the shaft 14 and has pivoted to one of its arms, as at 22, the pawl 23, the end of which pawl is adapted to engage one of the teeth of the ratchet wheel when 5 the rockable member is moved so that the pawl moves forwardly and on a reverse movement of the arm 24 of the rockable member, the ratchet wheel is moved in the direction of the arrow *d*. Pivoted to the 10 arm 24 as at 25 is an operating bar 26 which operating bar is provided with means 27 whereby the same may be adjusted as to length so as to vary the adjustment of the rockable member 21. The bar 26 is bifurcated as at 28 so as to form spaced arms 29 adapted to engage on each side of the hub of the large gear 10 so that the bar 26 will be guided in its longitudinal movement as the cam 30 which is carried by the hub of 15 the gear 10 engages the pivoted roller 31, which is pivotally mounted on a pin 32 of the bar 26. It will be seen that as the gear 10 rotates that the cam 30 will come into engagement with the roller 31, thereby causing the bar 26 to move radially from the center of the gear 10 so that the arm 24 will be forced outwardly and the pivoted dog 23, which engages one of the teeth of the ratchet and cause said ratchet wheel to rotate in 20 the direction of the arrow *d*. After the cam 30 has passed the pivoted roller 31 it will be seen that the bar 26 will slide to a position as shown in Fig. 1 so that the intermittent rotation of the ratchet wheel will be 25 repeated. The rotation being sufficient to move the male dies 19 a space equal to the distance they are spaced apart on the chains 17.

Pivotedly mounted on a shaft 33 carried 30 in spaced ears 34 at the forward end of the frame 1 is a pivoted jaw 35, which jaw comprises the sides 36 the lower ends of which are pivotally mounted on the shaft 33 and disposed between the spaced ears 34 of the 35 frame 1. Rockably mounted in bearings 37 of the upper ends of the sides of the jaw 35 are the pintles 38 of a rockable gripper member 39 which gripper member is adapted to rock slightly so that it will cause the 40 gripping elements to come out of engagement with the upper face 40 of the female die 41, which die is secured to lugs 42 carried by the inner faces of the arms 36 and held in place by means of bolts 43. When the 45 jaw 35 is moved outwardly the gripper member 39 is rocked so that the gripping elements will be opened as shown in dotted lines in Fig. 3, said gripping elements being adapted to be closed so as to engage the 50 metallic strip 44 and hold the same in registration with the female die when the same is moved inwardly against the male die 19 so that said male die will bend the strip 44 longitudinally. A transversely disposed bar 55 45 which is carried by the sides 2 of the

frame 1 is disposed behind the male die 19 when the same is going through a bending operation so as to form a solid foundation for said male die 19. Secured to a reduced portion 46 of the pinte 38 at one side of the 60 jaw 35 is a lever 47. The arm 48 of which lever extends upwardly and has connected to its end as at 49 a link 50, which link is pivotally connected as at 51 to the large gear 10, at a point near the edge of said gear 10, and as the gear 10 rotates the link 50 will force the arm 48 of the lever 47 in the direction of the arrow *e* which will cause the gripper member 39 to release the bent strip and at the same time will rock the arm 52 of the lever 47 in the direction of the arrow *f*, until the roller 53 carried thereby moves upwardly until it clears the arcuate surface 54. However during this movement the cam 30 of the large gear 10 will have 65 moved until it engages the roller 31, thereby causing the sprockets 16 to rotate in the direction of the arrow *g*, which rotation will move the male die which has just been in operation and on which the bent strip is 70 disposed upwardly and the adjacent male die 19 below moved into position for bending and receiving the next strip. After the roller 53 has cleared the arcuate surface 54 the further rotation of the large gear 10 75 will cause the pivoted jaw 35 to be moved outwardly to the position shown in dotted lines in Fig. 3, the roller 53 being in engagement with the cam surface 55. When the pivoted jaw is in the out position as 80 shown in Fig. 3 it will be seen that a strip may be placed between the gripping jaws and in registration with the female die 41 so that as the link 50 is again moved rearwardly by the rotation of the large gear 10, 85 the gripping member 39 will grip the strip immediately after it clears the cam surface 55 and engages the arcuate surface 54. However during this movement the jaw will be moved inwardly until the edge of the 90 male die strikes the center of the strip 44 and bends the same longitudinally so that a strip V-shaped in cross section is formed. The pinte 38 at the other end of the gripping member 39 is provided with an arm 56 95 similar in shape and length to the arm 48 of the lever 47 and pivoted to the end of said lever 56 as at 57 is a link 58. The other end of the link 58 is pivoted to an arm 59 as at 60 of a counterbalance 61 which is 100 carried by the shaft 11, which also carries the large gear 10 there being a counterbalance weight 62 oppositely disposed to the arm 59 and forming means whereby a positive action will be insured and the proper 105 momentum and power imparted to the moving parts.

It will be noted that each male die passes 110 upwardly and has disposed and frictionally held thereon the bent V-shaped strip, there- 115

fore to remove these strips automatically from the male dies 19, inclined lugs 63 provided on the inner faces of each of the frames so that as the dies 19 revolve and 5 pass the lugs 63, said lugs will engage under the ends of the bent strips and force the same from the dies, according to the direction of rotation of the dies 19. The above operation being possible by having 10 the bent strips extend slightly beyond the ends of the dies 19.

The strips to be bent are placed in the gripping jaws of the pivoted jaw when the gripping jaw 39 is in open position as shown 15 in dotted lines in Fig. 3. The feeding and placing of the strips 44 in the pivoted jaw is preferably done by hand and as the strip rests on a transversely disposed ledge of the female die 41 and as the jaw 35 is in an 20 inclined position, the initial movement of the arm 56 will move the gripping jaw 39 downwardly until it engages the upper edge of the strip 44 thereby holding the same against displacement. The further movement 25 rearwardly of the link 58 will cause the pivoted jaw 35 as a whole to move inwardly until the gripped strip 44 is bent longitudinally by the male die 19 which forces the same into the V-shaped longitudinal recess of the female die 41.

From the above it will be seen that a machine is provided for bending longitudinally strips of metal so that they will be formed substantially V-shaped in cross section and 35 by slightly varying the shape of the male and female dies, it will be seen that strips V-shaped in cross section may be formed with curves or compound curves so that they may be made to conform to various contour 40 shapes for use in connection with plow share edges.

The invention having been set forth what is claimed as new and useful is:—

1. A metal bending machine comprising a 45 frame, an endless chain vertically movable in said frame, dies carried by said endless chain, a pivoted jaw pivoted to the frame, said jaw having a die member, means for intermittently moving the chain carried dies 50 and means for moving the pivoted jaw inwardly during a bending operation.

2. A metal bending machine comprising a frame, an endless chain vertically movable in said frame, a pivoted jaw pivoted to the frame, metal bending dies carried by the 55 endless chain and by the pivoted jaw, means for intermittently moving the endless chain, and means for closing the jaw during a bending operation and opening the jaw 60 after a bending operation.

3. A metal bending machine comprising a frame, an endless chain vertically movable in said frame, a series of dies equally spaced

from each other and carried by said chain, a pivoted jaw pivoted to the frame and provided with a die, and means operated from a single source of power for moving the endless chain the distance that the dies thereon are spaced apart then moving the pivoted jaw inwardly and then moving the pivoted 70 jaw outwardly at the same time that an adjacent chain carried die is moved into operative position.

4. A metal bending machine comprising a frame, an endless chain vertically movable 75 in said frame, a series of dies equally spaced from each other and carried by the chain, a pivoted jaw pivoted to the frame, a gripping device carried by the jaw and adapted to grip and hold a piece of metal, a die carried by the pivoted jaw and disposed behind the gripping jaw held strip of metal, and means operated from a single source of power for moving the die carrying chain a distance equal to the space between its dies, 80 opening the gripping members, and moving the pivoted jaw outwardly.

5. A metal bending machine comprising a frame, an endless chain vertically movable in said frame, a series of dies equally spaced 90 from each other and carried by the chain, a pivoted jaw pivoted to the frame and provided with a die, a holding device carried by the jaw and adapted to hold a piece of metal in registration with the die carried by 95 the jaw, and means operated from a single source of power for intermittently moving the die carrying chain, closing the pivoted jaw at the same time closing the holding device so as to bend the strip of metal held 100 in the holding device and then open the pivoted jaw.

6. A metal bending machine comprising a frame, an endless chain vertically movable in said frame, a series of dies equally spaced 105 from each other and carried by the chain, a pivoted jaw pivoted to the frame and provided with a die, a holding device carried by the jaw and adapted to hold a piece of metal in registration with the die carried by the 110 jaw, means whereby power from a single source will close the holding device and the jaw and move the same inwardly against a die carried by the die carrying chain, open the jaw and move the adjacent chain carried 115 die into position to register with the jaw carried die on the next operation, and means for stripping the bent strips from the chain carried dies.

In testimony whereof I have signed my 120 name to this specification in the presence of two subscribing witnesses.

PETER AUGUST NORDQUIST.
